WALL AND CEILING COVERING.

No. 19,623.

Patented Jan. 28, 1890.

UNITED STATES PATENT OFFICE.

PAUL GROEBER, OF RUTHERFORD PARK, NEW JERSEY, ASSIGNOR TO
FREDERICK BECK, OF NEW YORK, N. Y.

DESIGN FOR A WALL AND CEILING COVERING.

SPECIFICATION forming part of Design No. 19,623, dated January 28, 1890.

Application filed December 26, 1889. Serial No. 335,056. Term of patent 3½ years.

To all whom it may concern:

Be it known that I, PAUL GROEBER, a citizen of the United States, residing at Rutherford Park, in the county of Bergen and State of New Jersey, have invented and produced a new and original Design for a Wall and Ceiling Covering, of which the following is a specification, reference being had to the accompanying drawing, forming part thereof.

10 The leading feature of my design consists of leaf-scrolls 1, forming volutes ornamented in center with floral decorations 2. Tendrils spring from scrolls which arrange themselves in lines at the upper 3 and the lower edge of 15 design 4. There is an upper 5 and a lower

border 6, consisting of plain molding and beads. The border is in some cases pierced by the scroll-work 8 and 9.

What I claim is—

The design for a wall and ceiling covering 20 herein shown and described, consisting of scrolls and volutes with floral centers, tendrils with volutes forming border, and an upper and a lower border of plain moldings and beads.

PAUL GROEBER.
